Patented Nov. 8, 1966

206,183

BRAKE CYLINDER GAUGE

Walter P. Kushmuk, Niles, Ill., assignor to Ammco Tools, Inc., Chicago, Ill., a corporation of Illinois

Filed Dec. 6, 1965, Ser. No. 68

Term of patent 14 years

(Cl. D52—6)

FIG. 1.

FIG. 2.

FIG. 3.

FIG. 4.

FIGURE 1 is a front view in elevation of the brake cylinder gauge embodying a handle member and a detachable brake cylinder gauge member characteristic of my new design;

FIGURE 2 is a top plan view of FIGURE 1;

FIGURE 3 is a right end view in elevation of FIGURE 1; and

FIGURE 4 is a left end view in elevation of FIGURE 1.

I claim:

The ornamental design for a brake cylinder gauge, as shown.
